RACK FOR PHONOGRAPH RECORDS OR THE LIKE

Helen Bogart, Cleveland Heights, Ohio, assignor of one-half to Arthur A. Newman, University Heights, Ohio

Application September 28, 1954, Serial No. 32,467

Term of patent 14 years

(Cl. D33—10)

Figure 1 is a side elevation of a rack for phonograph records or the like embodying my new design, and Figure 2 is a top plan view thereof.

The broken line showing of records is for illustrative purposes only.

I claim:

The ornamental design for a rack for phonograph records or the like, substantially as shown and described.
